CLAIM

The ornamental design for a video tape dispensing machine, as shown.

DESCRIPTION

FIG. 1 is a front perspective view of a video tape dispensing machine showing our new design;

FIG. 2 is a front elevation view thereof;

FIG. 3 is a right side elevational view thereof;

FIG. 4 is a rear elevational view thereof;

FIG. 5 is a left side elevational view thereof;

FIG. 6 is a top plan view thereof;

FIG. 7 is a bottom plan view thereof; and

FIG. 8 is an enlarged detail perspective view of the dispensing machine operating station as shown at the right hand front of the machine shown in FIG. 1.
